UNITED STATES PATENT OFFICE

MERLIN A. STICELBER, OF KANSAS CITY, MISSOURI, ASSIGNOR TO THE NAFZIGER CORPORATION, OF KANSAS CITY, MISSOURI, A CORPORATION OF MISSOURI

ENGINE CONTROL MEANS

Application filed February 6, 1930. Serial No. 426,271.

These improvements relate to means for controlling an internal combustion engine in various ways and to various effects by devices electrically operated.

5 The prime object is to provide simple and highly advantageous means for controlling an internal combustion engine; to provide an electric governor which may be associated with the timer mechanism; and, more specifically, one which may readily be installed as an attachment in connection with the timer mechanism of internal combustion engines already in use, or which may be part of the original construction. Other objects are to 10 provide a mechanism of this kind which is simple in construction, of few parts, one which occupies but little space, and one according to which the installation may be made in, or removed from, the timer device, 15 without prejudice to the normal functioning of the timer. Still other objects and advantages will appear hereinafter.

In the drawing Figure 1 is a fragmentary view of automobile parts in side elevation showing an application of the present governor device to control the speed of the engine whereby the speed of the vehicle may not rise beyond a predetermined amount;

Fig. 2 shows partly in elevation and partly in medial vertical section a well-known form of timer device having these improvements in a highly advantageous form applied thereto;

Fig. 3 is a horizontal section on the line 3—3 of Fig. 2;

Fig. 4 is a perspective of the tensioning spring for the governor device; and

Fig. 5 is a top view enlarged over that of Fig. 1 showing an air intake control device.

Referring to Fig. 2 the housing body member 10, the housing cap member 11, the distributor arm 12 with its contact member 13 on a leaf spring 14 and with the distributor 45 spark member 15 arranged to pass closely adjacent to the several terminals 16, with the timer shaft 17 extending through the bottom wall 18, may severally be considered old and well-known features of timer construction.

It is to be understood also that within the

housing body 10 there is other timer mechanism, all old and well-known, which it is deemed unnecessary to illustrate or describe in detail.

Such a timer as the one illustrated, omitting my novel features, has a pair of leaf springs 20 held respectively by pins 21 on lugs 22 with projections 23 respectively adapted by the manufacturer of the timer device to engage with a notch at 25 in the cap member 11. I have shown an intermediate housing member 26 between the body member 10 and cap member 11. If that intermediate member 26 and the governor were removed the cap member 11 would fit upon the body member 10, and the spring projection 23 would engage the notch at 25. I would then have the ordinary well-known timer without any of the present improvements added thereto.

The housing as a whole will ordinarily be a substantially cylindrical body. The ring 26 is of the same diameter as the coacting upper portions of the body 10 and the lower portions of the cap 11. The ring 26 has a 75 depending inner flange 27, which fits inside of the body wall 10 exactly the same as does the similar projection 28 on the cap member 11 when the ring 26 is removed. There is also an upstanding flange-like projection 29 80 on the ring 26 which is in all respects like the upper edge 30 of the body 10. The ring 26 therefore interfits with the body 10, and also with the cap 11 so as to lock the several parts together in all respects as cap 11 would be 85 locked directly to body 10 without the present improvements added.

Means for holding the cap 11 on the intermediate ring 26 are the two leaf springs 32 held likewise on pin 21, but with a leaf extension 32a which permits springs 32 to be applied and removed readily. These springs 32 are provided at their upper end portions respectively with projections 33 adapted to engage the notches 25. Ring 26 is provided with notches 34 adapted to be engaged by the projections 23 of springs 20. The springs 32 overlie springs 20 respectively. The cap and the intermediate ring may be readily removed by simply releasing first spring 32 100

and then spring 20 from their catch recesses respectively.

Fig. 2 shows that the timer shaft 17 has a notch or cut-out at 17a. The timer arm 12, 5 of insulating material, as of bakelite, has a recess 35 coaxial with shaft 17 adapted to accommodate the upper end of shaft 17 when the ring 26 is not present. As shown in Fig. 2 this recess 35 accommodates the upper end 10 of a short shaft or shaft-like connection 40 of insulating material, as bakelite, which is recessed or notched at 40a (Fig. 2) in all respects the same as is the upper end of shaft 17 at 17a. The arm 12 fitting upon this 15 shaft or connection 40 is therefore driven around when connection 40 is turned. The lower end 40b of shaft or connection 40 is formed in all respects the same as the lower end portion 12a of timer arm 12 so that the 20 lower end 40b fits upon the upper end of shaft 17 exactly the same as the lower end 12a would do without these improvements.

Fig. 3 shows a pair of trunnions 42 emerging diametrically from the shaft-like connection 40, and on these trunnions is an elongated metallic ring 43 mounted to swing on the trunnions 42. This construction provides what is frequently called a "wobble ring," or a wobble ring governor. Centrifugal force causes the ring 43 to assume a 25 position at right angles or more nearly at right angles to the power shaft as 17 with respect to its position shown in Fig. 2.

The spring 45 (Fig. 4) has a coil 45a passing around the exposed part of the shaft-like connection 40 and a pair of hook members 45b engaging the governor ring 43 as shown in Fig. 2. This spring tension normally causes the ring to assume the slanting position as shown in Fig. 2, and centrifugal force 35 moves the governor ring against the tension of spring 45. The tension of spring 45 may be adjusted by turning the nut 6 on screw shaft 7 passing through eye 8 (Fig. 4) of spring 45, there being a projection 9 on shaft connection 40 through which bolt 7 passes.

On the inner surface of housing ring 26 are two conductor half-rings 47 and 48 insulated from each other at 49 and 50. Spring brushes 51 and 52 oppositely secured 45 on the governor ring are adapted to contact these oppositely-disposed contact members 47 and 48 when centrifugal force has moved the governor ring into a more straight-across 55 relation. Binding posts 54 and 55 are connected to half-rings 47 and 48 respectively, and from these posts wires 56 and 57 extend to any suitable electric device to be controlled by the engine speed as interpreted at the 60 timer shaft 17.

Turning to Fig. 1 the carburetor 60 has a pipe extension having a flange 61, and intake manifold 62 has a similar flange 63. The shape of these flanges is the same as that of 65 member 64 in Fig. 5. The flanges 61 and

63 are found in practice to be bolted together. Plate-like member 64 is interposed and bolted between these flanges.

The hole 65 (Fig. 5) is a fuel passageway. Bore 66 is an air intake port covered by valve 70 on solenoid core rod 68 entering solenoid coil 69 secured to support 70 integral with member 64. The energizing wire 57 is shown as leading to the timer device of Figs. 2 and 3 while wire 58 leads to battery B and thence 75 wire 72 leads also to the governor device.

Referring to the application shown in Figs. 1 and 4, when the timer shaft rotates at a speed which denotes a predetermined engine speed, and therefore a predetermined vehicle speed, the governor device completes a circuit through contact half-rings 47 and 48 and through the governor ring 43, and thereupon the solenoid coil 69 is energized to retract valve 67 against the tension of spring 71. This controls the fuel supply by admitting air into the fuel passageway from the carburetor to the engine cylinders, diluting the fuel and slowing down the engine. The engine may not, therefore, drive the vehicle at 80 a rate higher than the predetermined one. The adjustment at 6, 7, 8 and 9 (Fig. 2) determines the speed at which the governor becomes effective.

Centrifugal governors have been suggested heretofore in connection with timer shafts, but only, so far as I know, to provide mechanical motion, such motion being suggested for controlling the engine speed, as by a valve 95 in the intake manifold. Such a mechanical operation involves a considerable number of mechanical parts and the application of considerable force, and more force, indeed, than it is possible to supply by means of a governor, unless the governor be quite large and having substantially heavy centrifugal members. Furthermore the association with the timer shaft of a governor adapted to provide such force as is necessary to operate control 100 devices mechanically entails a considerable burden upon the timer shaft and its connections, and one which is likely to interfere with the correct timing of the sparks for the engine cylinders.

According to these improvements, in their broader aspects, the only additional work put upon the timer shaft is the entirely negligible one of operating the electrical governor device, while the actual work to be done, say for moving a valve, of one kind or another, as 115 to control the engine, is performed electrically, as by a solenoid. The improvements in this aspect therefore provide that a small governor device may be employed, and one, as indicated, which may actually be within 120 the commutator or timer housing, and one which obviates the use of numerous mechanical constructions objectionable in many ways.

I contemplate as being included in these 125 improvements all such changes, variations 130

and departures from what is specifically illustrated and described herein as fall within the scope of the appended claims.

I claim:

- 5 1. A multiple-part housing for an engine timer or distributor of the character described which comprises a body member, an intermediate member and a cap member, with means for holding the cap member releasably upon the intermediate member, and other means for holding the intermediate member releasably upon the body member.
- 10 2. In a combined timer or distributor of the character described and a governor, the combination of a timer shaft, a centrifugal governor device readily attachably mounted on the inner end of said shaft for rotation thereby, and a distributor arm readily attachably mounted on the governor device to be rotated thereby, there being housing means encompassing the inner end of said shaft and said governor device, distributor terminals carried by the housing means for coaction with the distributor arm, and contacts adapted to cooperate with the rotating governor device.
- 15 3. In a combined timer or distributor of the character described and a governor, a timer shaft, a housing having a readily removable cap portion carrying distributor terminals, a governor device including a part

adapted to fit for ready removability upon the end of said shaft so as to be rotated thereby, and a distributor arm adapted to fit readily removably upon said part.

- 70 4. An attachment device for a timer or distributor of the character described having a housing comprising a body portion and a cap portion, and a timer shaft extending into the housing, said attachment device comprising an intermediate housing member adapted to fit between said body and cap portions, a governor device including a part adapted to fit upon the end of the timer shaft for rotation thereby, said part being formed to interfit also with a distributor arm adapted to fit also upon the end of said shaft, said intermediate housing member and said governor device having coacting contact means for controlling a circuit.

- 75 5. The combination with an internal combustion engine having a timer shaft, timer mechanism, and a housing for the timer mechanism, of an electrical centrifugal governor device in the form of an attachment having means for readily associating same with the timer mechanism and within said housing for operation by the timer shaft, with means for completing an electric circuit by the governor device when the latter reaches a predetermined speed.
